UNITED STATES PATENT OFFICE.

EDWARD C. HOLMES, OF CINCINNATI, OHIO.

CARRIAGE FOR DRILLING MECHANISM.

Application filed July 16, 1925. Serial No. 43,985.

My invention relates to carriages for drills and the like and particularly to a suitable carriage for supporting an electric drill for use in driving screw spikes into railroad ties for securing the rails to the ties and the tie plates.

It is the object of my invention to provide a carriage which will support an electric drill or the like in the chuck of which a screw spike may be secured, and which carriage will be easily movable and which will further provide simple means for aligning the drill or other mechanism with which the screw spike may be inserted into the railroad tie. It is further my object to provide adjustable features on my novel carriage which will permit adjustment for rails of different widths and rails which are aligned with different distances between the rails.

While my novel structure is primarily adapted to provide a carriage for drilling mechanism for securing screw spikes in railroad ties, the principle involved in the structure is with slight modifications adapted for use with a drill and equivalent devices with which bolts, screws, nails and other securing pieces may be driven in alignment so that although the specific example shown is adapted for a drill for securing screw spikes, I do not expect to limit myself to this particular structure, but to include modifications in structure with which equivalent functions may be performed.

Referring now to the drawings:

Figure 1 is a side elevation of the carriage.

Figure 1^a is an end elevation of the drill showing how it is mounted.

Figure 2 is an end elevation of the carriage, and

Figure 3 is a top plan view.

Generally indicated at 1 is the vertical frame member which is provided with bosses 2 and axles 3 which provide a suitable bearing for supporting the standard on the wheel 4. The wheel may be flanged if desired with a peripheral flange as indicated at 5. Suitably formed in the upright frame member another boss 6 is provided with a hole 7 in which a rod is secured with a set screw 8. The rod is bent and extends down to such distance above the aligned rail opposite the rail which is being secured with spikes, that it will act as an axle for a smaller wheel 9

which may be mounted on the axle and held 55 in adjustable position on the rod by means of collars disposed on each side of the wheel 9. The carriage is thus easily movable on the two rails of a track and a flange on the smaller wheel 9 as indicated at 10 provides 60 a simple way of keeping the carriage on the track and at the same time furnishing a suitable gauge with which the distance of the rails of the track from each other may be regulated and determined. The collars 9^a 65 may be secured in any desired position on the rod so that the wheels of the carriage may be set for any width track on which it is desired to work.

Forked arms 10^a are rigidly secured to the 70 top portion of the member 1 and these arms extend backwardly at approximately a right angle. They are provided with slots 11 extending vertically toward the track. These slots may be of any desired width and they 75 furnish the means of providing vertical guidance to the spider arms indicated at 11^a with which most drills are provided and which my carriage is adapted to support. I have indicated diagrammatically at 31 in Figures 80 1 and 1^a an electric drill suitable for use with my invention. The base of the slots naturally limits the downward movement of the drill or screw driving device for turning screw spikes into railroad ties. A lever arm 85 as indicated at 12 is pivotally mounted at 13 in the top of the frame member 1 and the long arms of the lever are forked and extend in alignment preferably on the outer side of the forked rigid arms 10^a. The lever arms 90 may be provided with extended hook-like portions 14 which are adapted to bear from above on the spider arms of the drill. The short arm of the lever is provided with a hole as at 15 or other suitable retaining 95 means to secure the end of a spring member 16 which extends from the short arm of the lever to a boss 17 on the upright member 1. The tension of this spring may be utilized 100 to counterbalance the weight of the drill so that pressure applied manually to the forked lever arms exerts a downward thrust on the drill in direct proportion to the pressure applied. I have found that an adjustable torsion spring in which the force of the 105 spring from a contracted position is utilized to counterbalance the weight of the drill is preferable. In the illustration shown I have

provided a hook member 19 secured in the hole in the short arm of the lever and this hook member is secured on the end of a rod 20 which extends through a hole in a disc 21 which the upper part of the spring abuts and down through the spring to another disc 22 at the bottom of the spring to which disc the rod is suitably secured with a nut. The upper disc is secured to another disc 23 on the same side of the spring as the disc 22, with tie rods 24. These rods pass through holes in the disc 22 and are secured to the outer disc 23 with adjustment nuts. As the nuts are tightened the contraction of the spring is increased and as the disc 23 is secured in the boss 17, it will readily be understood that the tighter the nuts on the tie rods are drawn down the greater will be the downward pull on the short arm of the lever.

In order to provide a positive adjustment element which will permit the use of the carriage with rails, the heads of which vary in width, I have pivotally mounted a clamp plate 25 on a backwardly extended part 26 of the frame of the carriage. The clamp plate is provided with lugs 27 which extend down over the rail and thus keep the carriage in the center of the rail. By turning this plate on its pivot which may be a stud bolt secured in the frame 26, the distance between the lugs 27 from the pivot point in a crosswise direction may be varied in accordance with the width of the head of the rail.

As the carriage must be provided with a means of aligning the drill so that it will drive the screw spike in a vertical direction I have provided another plate 28 which is mounted on the frame part 26 which extends at right angles to the direction of the rail and is provided with slots 29 on each side of the rail which extend in alignment with the rail. The slots 29 are of sufficient width to slidably retain the chuck of a drill so that when a screw spike has been secured in the chuck of the drill and the drill swung to position with the chuck within the slots, a spike driven with the drill will be in vertical alignment. In order to provide an indicator plate which will show the position on the tie plate indicated at 29^a through which a spike will be secured with the chuck of the drill in the slots 29, the plate 28 has strips extended down from the top of the rail as indicated at 30, which indicate the outer periphery of holes 30^a in the tie plate through which the spike is usually secured to the rail.

The operation of the carriage to hold a drill for driving screw spikes in railroad ties is as follows. The carriage is placed on the track and the clamp 25 adjusted for the width of the rail. The drill 31 is then seated with spider arms 11^a from the sides of the

drill disposed within the slots 11. A suitably sized alignment plate 28 in which the slots 29 are disposed in such position as to clear the base of the rail, is then secured to the carriage. The spring 16 is then tensioned so that the pivoted forked lever will have its handle adjacent the tops of the slots 11 and the drill will have a limit of vertical downward movement from the top part of the slots to the bottom which will give sufficient clearance to provide working room for the insertion of the spikes in the chuck. The position of the spikes is indicated by the extended pieces 30, and the labor of firmly securing rails with screw spikes is thus rendered an easy and fast operation.

The weight of the carriage in use is distributed between the wheel 4 and the clamp plate 25 but when it is desired to advance the carriage on a rail by raising the handles of the lever arms, the weight may be thrown all onto the wheel 4 so that the carriage may be moved on the rail similarly to the usual movement of a wheel barrow. It will further be noted that the support for the guide wheel 9 may be adjusted on either side of the frame so that the carriage may be used in either a right hand or left hand position on either of the two rails of a track.

Having thus described my invention, what I claim as new and desire to secure by Letters Patent, is:—

1. A screw spike driver carriage comprising, an upright member provided with a carrying wheel, a forked frame member secured to the upright member, vertical slots in the forked frame adapted to guide spider arms of a drilling mechanism or the like, and a pivoted rocker arm member with forked arms in alignment with the forked frame member extended so as to carry spider arms within the guiding slots.

2. A screw spike driver carriage comprising an upright member provided with a carrying wheel, a forked frame member secured to the upright member, vertical slots in the forked frame adapted to guide spider arms of a drilling mechanism or the like, and a pivoted rocker arm member with forked arms in alignment with the forked frame member extended so as to carry spider arms within the guiding slots and means for counterbalancing the weight of the driver.

3. A carriage for a drill or the like adapted to provide means of securing screw spikes in railroad ties comprising in combination a frame, with members adapted to carry the frame on rails of a track, and a portion of the frame provided with vertically disposed slots for guiding arms extended from a drill, a forked rocking lever with long arms of the lever adapted to carry the drill by means of its said arms, means connected with the short arm of the rocking lever and adapted to counterbalance the weight of a drill, and

means for vertically aligning a chuck of the drill with the track on which the carriage is adapted to ride.

4. A carriage for a device for inserting screw spikes comprising a frame, members adapted to carry the frame on rails of a track, a portion of the frame provided with vertically disposed slots for guiding arms

extended from said device, a forked rocking lever with long arms adapted to carry such a device, said lever having means connected therewith for counterbalancing the weight of such a device and means for aligning said carriage on a rail.

EDWARD C. HOLMES.
